(57) **CLAIM**

The ornamental design for fastener for solar modules, as shown and described.

DESCRIPTION

FIG. 1 is a first perspective view of a fastener for solar modules according to the present invention;

FIG. 2 is a second perspective view thereof;

FIG. 3 is an exploded perspective view thereof;

FIG. 4 is a top plan view thereof;

FIG. 5 is a bottom plan view thereof;

FIG. 6 is a front elevation view thereof, the rear elevation view being a mirror image;

FIG. 7 is a side elevation view thereof, the opposite side elevation being a mirror image;

FIG. 8 is a front elevation view thereof, shown in environmental use;

FIG. 9 is an exploded front elevation view thereof;

FIG. 10 is a side elevation view thereof, shown in environmental use; and,

FIG. 11 is an exploded side elevation view thereof.

The broken lines shown represent unclaimed subject matter and form no part of the claimed design.
